UNITED STATES PATENT OFFICE.

WILLIAM P. CRARY, OF NEW YORK, N. Y.

DESIGN FOR A LAMP-BRACKET.

SPECIFICATION forming part of Design No. 32,528, dated April 17, 1900.

Application filed March 7, 1900. Serial No. 7,734. Term of patent 3½ years.

To all whom it may concern:

Be it known that I, WILLIAM P. CRARY, a citizen of the United States, residing in the city of New York, borough of Manhattan, in the county and State of New York, have invented and produced a certain new and original Design for a Lamp-Bracket, of which the following is a full, clear, and exact specification, reference being had to the accompanying drawings, forming part thereof.

Figure 1 is a view of one face. Fig. 2 is a corresponding view of the opposite face, and Fig. 3 is a cross-section on the line 3 3 in the preceding figures.

The leading feature of my design is the general L-shaped bracket having a circular boss at one end and a perforated rectangular portion at the other end. Each face of the bracket is a counterpart of the other.

Similar letters of reference indicate the same parts in all the figures.

A is the main portion of the bracket, and A' an arm thereof extending at a right angle

from the body and forming with the latter the L shape described. At the end of the main portion is a circular boss A², having a central perforation a and radial depressions a'. The end of the arm A' terminates in an extension A³, parallel with the main portion and having countersunk perforations a². The main portion and arm have a raised bead A⁴ along each edge, producing the cross-sectioned form shown in Fig. 3, while the bars and extension are plane, excepting for the perforations and depressions a, a', and a². The faces of the bracket are alike on both sides, as shown.

I claim—

The design for a lamp-bracket herein shown and described.

In testimony that I claim the design above set forth I affix my signature in the presence of two witnesses.

WILLIAM P. CRARY.

Witnesses:

CHARLES R. SEARLE,
FRANK G. STARK.
